US00D876557S

(12) **United States Design Patent** (10) Patent No.: **US D876,557 S**
(45) Date of Patent: **** Feb. 25, 2020**

(54) **EXERCISING APPARATUS**

(71) Applicant: **NATURAL CREATE INC.**, Osaka
(JP)

(72) Inventor: **Yasutoshi Tajima**, Osaka (JP)

(**) Term: **15 Years**

(21) Appl. No.: **35/504,969**

(22) Filed: **Nov. 15, 2017**

(80) **Hague Agreement Data**

Int. Filing Date: **Nov. 15, 2017**

Int. Reg. No.: **DM/098886**

Int. Reg. Date: **Nov. 15, 2017**

Int. Reg. Pub. Date: **May 18, 2018**

(30) **Foreign Application Priority Data**

Jun. 1, 2017 (JP) 2017-11809

(51) **LOC (12) Cl.** **21-02**

(52) **U.S. Cl.**

USPC **D21/678**

(58) **Field of Classification Search**

USPC D21/662, 668-672, 678, 686, 695-697

CPC A63B 21/0084; A63B 2208/03
